LIFE BUOY FLOAT

Gerald R. Lindberg, San Francisco, Calif.

Application April 18, 1955, Serial No. 35,552

Term of patent 14 years

(Cl. D71—1)

Fig 1

Fig 2

Fig. 1 is a perspective view of my life buoy float; and Fig. 2 is a top plan view thereof.

I claim:

The ornamental design for a life buoy float, substantially as shown.
